RADIANT ENERGY DETECTOR

Donald M. Szeles, Ann Arbor, Mich., assignor to
Sensors, Inc.

Filed Mar. 2, 1971, Ser. No. 120,377

Term of patent 14 years

Int. Cl. D10—05

U.S. Cl. D26—1

FIG. 1

FIG. 2

FIG. 3

FIG. 4

FIG. 5

FIG. 6

FIG. 1 is a front perspective view of a radiant energy detector showing my new design;

FIG. 2 is a side elevational view of FIG. 1 on an enlarged scale;

FIG. 3 is a front elevational view of FIG. 2;

FIG. 4 is a top plan view thereof;

FIG. 5 is a rear elevational view thereof;

FIG. 6 is a bottom plan view thereof.

I claim:

The ornamental design for a radiant energy detector, substantially as shown.
